(57) **CLAIM**

The ornamental design for a putter head, as shown and described.

DESCRIPTION

FIG. 1 is a perspective view of an putter head in accordance with this invention;

FIG. 2 is a top plan view of the putter head of FIG. 1;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a perspective view of an alternate surface finish for this invention as shown in FIGS. 1-7; and,

FIG. 8 is a perspective of a second embodiment of the putter head as disclosed in FIG. 1, the undisclosed sides are identical to that disclosed in the first embodiment.

The broken line showing is for illustrative purposes only and forms no part of the claimed design.
